UNITED STATES PATENT OFFICE.

GEORGE W. LANDENBERGER, OF PHILADELPHIA, PENNSYLVANIA, ASSIGNOR
TO CHARLES M. McCLOUD, OF SAME PLACE.

CHRISTMAS-TREE ORNAMENT.

SPECIFICATION forming part of Letters Patent No. 362,017, dated April 26, 1887.

Application filed December 4, 1886. Serial No. 229,655. (No model.)

To all whom it may concern:

Be it known that I, GEORGE W. LANDENBERGER, a citizen of the United States, residing in the city and county of Philadelphia, State of Pennsylvania, have invented a new and useful Improvement in Christmas-Tree Ornaments, which improvement is fully set forth in the following specification and accompanying drawings, in which—

10 Figures 1 and 2 represent elevations of Christmas tree ornaments embodying my invention.

Similar letters of reference indicate corresponding parts in the two figures.

15 My invention consists of a Christmas-tree ornament formed of a ball having a reflecting-surface and a frill, wreath, or other surrounding of tinsel, whereby brilliant effects are produced, as will be hereinafter fully set forth.

20 Referring to the drawings, A represents a ball formed of glass or other material having a glossy or reflecting surface.

B represents tinsel, which encircles the ball A, and is secured thereto by a wire, C, or other suitable means, said tinsel being of the form of a wreath in Fig. 1 and a frill in Fig. 2. Flies D are secured to the tinsel in Fig. 1; but to this I do not limit my invention.

If desired, a number of balls may be employed in lieu of the single ball shown in the drawings.

Attached to the ball or tinsel is a loop or hook, E, which may be continuous of the wire is C, and adapted for attaching the ornament to the tree.

It will be seen that the tinsel is reflected by the ball A, and, as it is of a glittering nature and possesses reflecting qualities, a brilliant effect is produced, this being further increased when the ornament is hung on a Christmas-tree and the latter illuminated.

Having thus described my invention, what I claim as new, and desire to secure by Letters Patent, is—

1. A Christmas tree ornament consisting of a ball having a reflecting-surface and tinsel surrounding the same and secured thereto, substantially as described.

2. A Christmas-tree ornament consisting of the ball A, having a reflecting-surface, the tinsel B, connected to the said ball A by wire C, and the loop E, substantially as described.

GEO. W. LANDENBERGER.
